UNITED STATES PATENT OFFICE.

EDWARD SPENCER, OF ST. LOUIS, MISSOURI.

IMPROVEMENT IN MARKING-MACHINES.

Specification forming part of Letters Patent No. 36,243, dated August 19, 1862.

To all whom it may concern:

Be it known that I, EDWARD SPENCER, of the city of St. Louis, in the State of Missouri, have invented certain new and useful Improvements in Marking-Machines; and I do hereby declare the following to be a full, clear, and exact description of the same, reference being had to the annexed drawings, making part of this specification, in which—

Figure 1 is a side elevation of my said machine. Fig. 2 is a face view of the jaw A' as far back as the line B' of Fig. 1, and Fig. 3 is a longitudinal section taken on the line C' of Fig. 2.

The object of my invention is to furnish a simple, cheap, and efficient marker, with which a railroad conductor can perforate, mark, or print the name of the road, date, &c., on the ticket, or with which a merchant can print his name on his goods, and at the same time he so small that it may be carried about in the pocket without inconvenience.

It consists of the following-described combination of mechanical devices, so as to effect the ends aforesaid.

Fig. 1 represents a pair of ordinary pinchers made upon an enlarged scale for the purpose of more fully illustrating the invention. The jaw A' of the aforesaid pinchers is made hollow, somewhat in the form of a trough, in about the center of which a die, N, is fitted, which die is mortised, as shown by b' b, so as to receive type to mark the month and the day of the month. The name of the railroad or individual is cut around the edge of the die at c, as indicated by the red lines. The said die is fitted in a box, as shown, which box is dovetailed through the side of the jaw and between the lugs x, made in the bottom thereof, and said box and die are held in their place by means of a button or screw on the side of the jaw. (Not shown in the drawings.) In the bottom of said box and under said die a piece of india-rubber is fitted, with a thin plate over it, as shown by P. The object of this yielding bottom under the die is to allow the die to adjust itself perfectly against the platen, which consists of the under side of the jaw A of the pinchers, against which some soft material is fixed, as at a, for the die to press against. The front end of the jaws being farther from the center of motion, open wider than their rear

ends do, so that if anything thick be placed between them they will not shut down parallel upon it, and hence the necessity of the yielding bottom under the die to allow its whole face to come up fair against the thing to be marked. The pinchers might be made so as to cause their jaws to open parallel with each other, and I shall make them so if I find it necessary; but for all practical purposes the yielding material under the die answers just as well and is cheaper.

H H represent two rollers—one on each side of the die—fixed in the jaw A'. On each of these rollers, a small spring-clasp is made. (Shown by v.) The object of these clasps is to secure a ribbon which is wound around said rollers and stretched from one to the other over the face of the die. The said ribbon is saturated with ink, and is kept tight over the face of the die by means of friction wheels or collars d d, which work against the pieces of india-rubber L L fitted in the jaw under them for that purpose. Said rollers are turned by means of small chased wheels e e on the outer end of the axis, in the manner shown.

A punch is fixed in the outer end of the jaw A', as represented by B. This punch consists of one steel tube working over another, with a spring, F, working over the lower and smaller one to raise the ticket or card off the punch when the jaws open.

A perforator is fitted against the side of the jaw A, as represented by C, the object of which is to perforate the card or ticket, so that it may be easily torn apart. The points of said perforator work in a piece of leather or other soft material fixed against the side of the jaw A' by means of the cleat E in the manner shown.

A link, D, is pivoted to the jaw A' in the manner and relation shown, so as to swing over and catch on the jaw A when the two jaws are closed, for the purpose of holding them together, that the pinchers may be as unobjectionable as possible in the pocket.

Most of the devices and combination herein described are shown and described in the patent granted to me on the 11th of February, 1862, but are not claimed therein. I do not intend, therefore, to claim the second time what has already been patented to me; but as I have made some additional improvements to

my stamp since the aforementioned patent was granted, and as I desire to claim more fully the combination shown and described in said patent, I have concluded to apply for a new patent embodying my improvements, and claim all the combinations not claimed in the patent aforesaid, describing and showing fully the whole in this application.

What I claim, therefore, and desire to secure by Letters Patent, is—

1. In combination with the jaws A A', the die N, substantially in the manner described, for the purpose specified.
2. In combination with the jaws A' A and die N, the yielding bottom r under the die, as shown and described.
3. In combination with the jaws A' A, rollers H H', and friction-wheels d d', the india-rubber friction-pieces L L', as shown and described.

4. In combination with the jaws A' A, the perforator C, as shown and described, for the purpose specified.

5. In combination with the jaws A' A and perforator C, the punch B, as shown and described.

6: In combination with the jaws A' A and die N, the punch B, as shown and described, for the purpose specified.

7. In combination, the jaws A' A, the perforator C, the die N, and the rollers H H', as described.

In witness that the above is a full description of my said invention I have hereunto set my hand this 15th day of March, 1862.

E. SPENCER.
